United States Patent

Des. 237,638
Patented Nov. 11, 1975

237,638

AMUSEMENT GAME CABINET

Joseph V. Kessler, Phoenix, Ariz., assignor of a fractional part interest to Robert J. Walton

Filed Feb. 19, 1974, Ser. No. 443,709

Term of patent 14 years

Int. Cl. D21—01

U.S. Cl. D34—5 J

FIG. 1 is a perspective view of the amusement game cabinet showing the front, side and top;

FIG. 2 is a plan view of the amusement device of FIG. 1 showing the front of the device; and

FIG. 3 is a perspective view showing the bottom, rear and other side of the device.

In FIGS. 2 and 3, the legs have been shown fragmentarily for convenience of illustration.

I claim:

The ornamental design for an amusement game cabinet, as shown and described.
